PULPWOOD BOXCAR UNLOADER

Carey A. Thompson, Georgetown, S. C.

Application June 6, 1951, Serial No. 230,219

11 Claims. (Cl. 214—47)

I This invention relates to new and useful improvements in box car unloaders and more particularly to those especially useful in the unloading of pulpwood.

Many unloaders heretofore have been developed which are tiltable about two axes to facilitate the dumping or discharging of their contents. All of these unloaders, however, have been directed to the unloading or discharging of grain, gravel, coal or similar free flowing products.

Prior types of unloaders have not been useable in connection with box cars carrying pulpwood since the logs jammed and could not be removed by dumping but had to be manually unloaded, which is a slow and dangerous operation.

Therefore, it is an object of this invention to provide a pulpwood box car unloader, which may be tilted about two axes, and provided with a reciprocating baffle to impart outward movement to the pulpwood logs contained therein.

It is another object of this invention to provide a box car unloader of the character described, including a primary baffle carriage to move the baffle inward through the box car at the door areas or to move the baffle outward until completely free of the box car so that the car can be moved on and off the platform.

It is another object of this invention to provide a box car unloader of the character described including a secondary baffle carriage carried by and movable independently within the primary baffle carriage and a baffle carried by the secondary baffle carriage and means to drive both baffle and secondary carriage in short reciprocating strokes so that the baffle may impart outward movement to pulpwood logs within the box car.

Another object of this invention is to provide a box car unloader of the character described in which the baffle is provided with diagonal protruding ribs to impart both upward and outward movement to pulpwood logs to thereby facilitate discharge thereof from the box car.

A further object of this invention is to provide a box car unloader of the character described which can be quickly and mechanically adjusted to operate with different sizes of cars.

With these and other objects in view, the nature of which will be more apparent, the invention will be more fully understood by reference to the drawings, the accompanying detailed description, and the appended claims.

In the drawings,

Fig. 1 is a partly schematic side elevation of a box car unloader constructed in accordance with

this invention with certain portions removed in the interests of clarity, and with its tilted positions indicated by broken lines.

Fig. 2 is an end elevation thereof with the tilted positions indicated by broken lines.

Fig. 3 is an enlarged top plan of the central portion thereof, partly in section, and showing the baffle plate and carriage within the box car.

Fig. 4 is an enlarged detail end elevation showing the baffle plate and carriage withdrawn from the box car.

Fig. 5 is an enlarged detail longitudinal section taken along line 5—5 of Fig. 4. In the interests of clarity certain portions covering the drive mechanism have been removed.

Fig. 6 is an enlarged fragmentary detail top plan view of the drive mechanism for the baffle plate.

Fig. 7 is an enlarged detail elevational view, partly in section, of the baffle plate and its mounting means.

Fig. 8 is an enlarged detail horizontal section taken along lines 8—8 of Fig. 7 and extends to the end of the baffle; and

Fig. 9 is somewhat schematic enlarged fragmentary vertical section taken along line 9—9 of Fig. 8 and shows the automatic leveling device for the baffle.

Referring to the drawings in detail, this invention as illustrated is embodied in a box car unloader particularly adapted for unloading pulpwood and includes a primary cradle A tiltable about a transverse axis, a secondary cradle B pivotally attached to said primary cradle and tiltable about a longitudinal axis, a box car C held on rails carried by said secondary cradle, a primary baffle carriage D movably carried by said secondary cradle, and a secondary baffle carriage E movably carried by said primary carriage and provided with a baffle F adapted to be inserted into and withdrawn from the door areas of the box car. The details of the tilting mechanism per se do not form a part of this invention, but are generally included in order to illustrate the application of the present invention.

The primary cradle A comprises an open platform 10 having a pair of spaced quadrants 12, 12 depending therefrom and movably supported on a plurality of roll supports 14. The cradle A may be tilted either to the right or left as viewed in Fig. 1 about a transverse axis by driving the quadrants 12 through the medium of a pair of cables 16, 16 each of which has its ends fastened to the platform 10 adjacent the ends of the quadrants and its middle portion passed one or more

times around a driving drum 18 driven by suitable motor and gear reduction means generally indicated at 20.

The secondary cradle B comprises an open platform 22 having a pair of spaced segmented gears 24, 24 depending therefrom and respectively meshing with a pair of pinions 26, 26. The cradle B may be tilted to one side only, to the left as shown in Fig. 2, about a longitudinal axis 28 by suitable motor and gear reduction means generally indicated at 30. The secondary cradle B is pivotally attached to the primary cradle A through a plurality of hinges 32 located along the axis 28 and attached to the respective open platforms 10 and 22. An I-beam 33 is secured to the primary platform 10 as shown in Fig. 2 so that the edge of the secondary platform 22 rests levelly on the I-beam when the secondary platform is in its non-tilted position.

The open platform 22 is provided with steel rails 34, 34 so arranged that a box car may be moved easily on and off the unloader. A pair of end clamps 36, 36 are provided in the open platform to clamp and center the box car. Said clamps are operated by a motor 38 which may be wired to cut off automatically when the car is secured by the clamps and centered. A long shaft 39 is operably connected to the motor and driven thereby. Each end of the shaft is threadably engaged with one of the end clamps.

A plurality of spaced parallel flanged beams 40 extend laterally from one side of the open platform 22 and carry the box car bracing. The flanged beams 40 are braced by beams 42 extending from the outer ends thereof to a depending portion of the secondary cradle B to prevent sagging. A box-like frame 44 is slidably carried by each beam 40 and can be moved in or out by a motor 46 through a shaft 48 threadably engaged in a fitting 50 attached to the frame 44. It should be noted that the motor 46 is located on the opposite side of the open platform 22. Each frame 44 has rigidly mounted thereon a vertically disposed beam 52 braced by a beam 54. One or more of the beams 52 may be provided with a limit switch 56 near the top. The beams 52 are of such a height that their upper ends are slightly below the top of the box car. The limit switches 56 are adapted to automatically stop the motors 46 when the beams 52 have been moved flush against the side of the box car.

A pair of spaced parallel horizontally disposed supporting beams 58, 58 extend laterally from the open platform 22 and are located on the side opposite the box car braces 52. A beam 59 extends between the outer ends of the beams 58 and is rigidly attached thereto. A plurality of bracing beams 60 extend between the outer ends of the beams 58 and a depending portion of the secondary cradle B to prevent sagging.

The primary baffle carriage is formed from a framework of beams 62 and is mounted on a plurality of trolleys 64 which roll on the supporting beams 58. The primary carriage is moved along the supporting beams by a motor drive coupled to one end of a long threaded shaft 68 threadably engaged in a fitting 70 attached to the primary carriage. The motor 66 is mounted on a platform 72 built on the supporting beams 58, and the other end of the threaded shaft 68 is journaled in a bearing 73 provided at the center of a cross-beam 74 of a bearing stand including vertical and angular legs 76. Immediately adjacent the platform 72 a pair of vertical posts 75 rise from the respective supporting beams 58 to 75

a height slightly above the motor 66. A horizontal roller 77 extends between the two vertical posts 75 and supports the weight of the outer or unsupported portion of the baffle F when the baffle is withdrawn as shown in Fig. 4.

A narrow rectangular cage is formed within the primary baffle carriage and is defined by four vertical posts 78 extending up from the primary carriage base (see Fig. 3), the cage forming a housing for the secondary baffle carriage. The housing is centered transversely in the primary carriage but extends thereabove (Fig. 5). A supporting beam 80 extends horizontally from the front to the rear vertical post on both sides. A top guide beam 82 extends the length of the housing and is firmly secured between the tops of the respective front and rear pairs of vertical posts 78. A bottom guide beam 84 runs parallel to the top guide beam 82 and is located immediately above the threaded shaft 68 as shown in Figs. 4 and 5. The bottom guide beam is also fastened between the respective front and rear pairs of vertical posts 78.

The secondary baffle carriage E is movably carried by a plurality of bottom rollers 86 and top rollers 88 which respectively are engaged with the bottom and top guide beams 84 and 82. The secondary baffle carriage is formed of a bottom horizontal beam 90 from which the lower rollers 86 depend, a rear vertical beam 92, a front vertical beam 94, and a top horizontal beam 96 from which the rollers 88 extend. These four beams form a rectangle, but with the top and bottom beams extending somewhat beyond the front beam, for reasons to be explained hereinafter. In front of and parallel to the front vertical beam 94 is a rotatable steel shaft 98 which is mounted in a thrust bearing 100 at the bottom on the beam 90 and in a babbitted collar bearing 102 at the top within the beam 96. A bevel gear 104 is secured to the upper projecting end of the shaft 98 and is positioned immediately above the top beam 96. Another bevel gear 106 is attached to the shaft 110 of a motor 108 mounted on the projecting end of the beam 96 and meshed with the gear 104 to drive the shaft 98. The lower portion of the shaft 98 is provided with heavy jack screw threads 112. A collar 114 is threadably carried on the threads 112 of the shaft. The collar is provided with an arm 116 which is slidably connected to a small rod rigidly mounted outwardly of the beam 94 so that the collar 116 is permitted to move in a vertical plane but cannot rotate. Thus when the shaft 98 is rotated the collar 116 moves up or down, depending on the direction of shaft rotation.

The baffle F is formed from a framework of I-beams 120 which are covered by steel plates 122 to form a wedge as shown in Fig. 8. A plurality of slanting, protruding ribs 124 are attached to both outer surfaces of the baffle except for about 2 feet adjacent the outer end for reasons which will be explained hereinafter. The inner end of the baffle is welded to a heavy pipe or sleeve 126 having a diameter such that it can pivot freely about the shaft 98 as shown in Figs. 7 and 8.

The outer end of the baffle is provided with an automatic leveling device as shown in Fig. 9 so that in operation the lower edge of the baffle will be positioned in a plane slightly higher than the box car floor to permit unobstructed entry of the baffle into the car. The leveling device includes a sensing arm 128 pivotally connected to the baffle at 130 and provided on its inner

end with a short upwardly projecting extension arm 132. A limit switch 134 is positioned adjacent the arm 132 and is provided with an L-shaped tripper or operating lever 136 engageable with the outer end of the arm 132. A solenoid 138 having a plunger 140 is secured within the baffle above the limit switch 134 and is connected to the sensing arm 128 through cord and pulley connections 142 and 144 to retract the sensing arm into the baffle after a leveling operation has been completed. The limit switch is connected by suitable wiring (not shown) to the motor 108 and to the solenoid 138.

The baffle is reciprocated by a motor 146 through a right angle gear reduction unit 148 of variable speed. The rotary motion of the motor is converted to the reciprocating motion of the baffle by means of a crank 150 and a connecting link 152 as shown in Figs. 3, 5 and 6. The crank shaft is provided with a fly wheel 154. The connecting link 152 is attached to the crank by means of a removable pin 160 which may be placed in any one of a plurality of apertures 158 in the crank to vary the length of the baffle stroke. The connecting link is bifurcated at the outer end and is provided with a removable wrist pin 160 by which it is attached to a lug 162. The lug is provided with an aperture 164 for the wrist pin 160 and is welded or otherwise secured to the front vertical beam 94.

In operation the box car C is first pulled onto the open platform 22 and centered and locked by the end clamps 36, 38 through operation of the motor 38. The motors 46 are then energized, rotating the threaded shafts 48, thus drawing the side bracing along the beams 40 until the vertical beams 52 are stopped flush against the side of the box car by means of the limit switches 56. With the bracing in position the motor 30 is actuated long enough to tilt the box car transversely to a 45° angle, causing the wood stacked in the door of the box car to slide out.

The proper level of the baffle should be established now by means of the automatic leveling device so that the baffle will clear the box car floor. The sensing arm 128 is released falling to the edge of the floor and the motor 108 started, thus rotating the threaded shaft 98 and raising the baffle. As the baffle rises, the sensing arm remains on the box car floor and so moves the tripper or operating lever 136 until the limit switch 134 is activated which in turn stops the motor 108 and activates the solenoid 138, causing retraction of the sensing arm into the baffle. Then motor 66 is started which rotates the threaded shaft 58 and draws the primary baffle carriage D forward until the baffle F is extended through both box car doors 156, 166.

With the baffle extended entirely through the box car at the proper level the motor 20 is actuated long enough to tilt the box car lengthwise to an angle of approximately 47°, causing the baffle to pivot about the shaft 98 so that the outer end swings to the lower side of the box car door. The motor 146 is then activated to reciprocate the baffle in short strokes. The cyclic speed of the baffle may be adjusted through the variable speed reduction unit 148 and the length of the stroke adjusted by changing the connecting rod 152 setting in crank shaft 150 as explained hereinbefore. Gravity will cause the legs to slide toward the baffle and

then the reciprocation of the baffle will deflect and force the legs outward. The protruding ribs 124 serve a very important function. The ribs tend to raise the legs as well as force them outward which serves to minimize the possibility of legs jam and damage to the box cars. It has been found that a smooth baffle, either stationary or oscillating, will not work satisfactorily. If the protruding ribs were placed at right angles to the lower edge of the baffle numerous jams occurred. Through experimentation it was found that the most efficient rib angle was 40° from the horizontal or lower edge of the baffle, pointing down toward the outer end of the baffle. As pointed out hereinbefore, the baffle is bare of ribs for approximately two feet at the outer end. This enables the baffle to move back and forth over the far door facing of the box car without mutilating the same. When the high end of the box car has been emptied the car is tilted lengthwise to reverse the high and low ends. The baffle pivots freely to the other side of the door, and the same unloading procedure is followed until the box car is emptied.

After the car has been emptied it is tilted back to the level position. The baffle is removed by motor 66 through threaded shaft 68. The vertical beams 52 are moved away from the side of the car by motor 46 through threaded shaft 48. The end clamps 36, 38 are unlocked by motor 38 and removed and the box car is pulled off the platform so that another car may be pulled on.

A box car unloader has thus been developed that will handle pulpwood and such other products as do not fall into the free-flowing class of goods. Pulp mills always require voluminous amounts of pulpwood which always causes a high cost handling operation in the wood yard if unloading can only be manually effected.

Thus it will be seen that the invention herein disclosed provides a box car unloader which can be successfully used with pulpwood and other non-free-flowing materials, wherein the box car is securely braced, tilted both transversely and lengthwise and provided with a reciprocating ribbed baffle extended through the box car to eject the pulpwood.

It is, of course, to be understood that various details of arrangement, proportions of parts and sequence of events may be modified within the scope of the appended claims.

I claim:

1. In a pulpwood box car unloader of the character described, a plurality of laterally projecting supporting beams, a primary baffle carriage movably mounted on said supporting beams, means to move rectilinearly said primary carriage, a secondary baffle carriage movably carried within said primary carriage, a baffle mounted on said secondary carriage, means to adjust the height of said baffle relative to said carriage, means to reciprocate said baffle and secondary carriage, said baffle being provided on both faces with a plurality of angularly disposed ribs, said ribs each being positioned at a 40° angle from the horizontal and pointing downwardly toward the outer end of said baffle.

2. In a pulpwood box car unloader of the character described, a plurality of laterally projecting supporting beams, a primary baffle carriage movably mounted on said supporting beams, means to rectilinearly move said primary carriage, a secondary baffle carriage movably carried within said

primary carriage, a vertically disposed shaft rotatably mounted on said secondary carriage, a baffle mounted on said shaft for axial movement with respect thereto, means for effecting axial movement of said baffle along said shaft, means to reciprocate said secondary carriage and said baffle, and means to change the stroke of reciprocation of said secondary carriage and said baffle.

3. In a pulpwood box car unloader of the character described, a plurality of laterally projecting supporting beams, a primary baffle carriage movably mounted on said supporting beams, means to rectilinearly move said primary carriage, a secondary baffle carriage movably carried within said primary carriage, a vertically disposed shaft rotatably mounted on said secondary carriage, a baffle mounted on said shaft for axial movement with respect thereto, means for effecting axial movement of said baffle along said shaft, means to reciprocate said secondary carriage and said baffle, means to change the stroke of reciprocation of said secondary carriage and said baffle, and means to change the speed of reciprocation of said secondary carriage and said baffle.

4. In a pulpwood box car unloader of the character described, a plurality of laterally projecting supporting beams, a primary baffle carriage movably mounted on said supporting beams, means to rectilinearly move said primary carriage, a secondary baffle carriage movably carried within said primary carriage, a vertically disposed shaft rotatably mounted on said secondary carriage, a baffle mounted on said shaft for axial movement with respect thereto, means for effecting axial movement of said baffle along said shaft, means to reciprocate said secondary carriage and said baffle, and means to change the stroke of reciprocation of said secondary carriage and said baffle, said baffle being provided on both faces with a plurality of angularly disposed ribs.

5. In a pulpwood box car unloader of the character described, a plurality of laterally projecting supporting beams, a primary baffle carriage movably mounted on said supporting beams, means to rectilinearly move said primary carriage, a secondary baffle carriage movably carried within said primary carriage, a vertically disposed shaft rotatably mounted in said secondary carriage, a baffle mounted on said shaft for axial movement with respect thereto, means for effecting axial movement of said baffle along said shaft, means to reciprocate said secondary carriage and said baffle, means to change the stroke of reciprocation of said secondary carriage and said baffle, said baffle being provided on both faces with a plurality of angularly disposed ribs, and means to change the speed of reciprocation of said secondary carriage and said baffle.

6. In a pulpwood box car unloader of the character described, a plurality of laterally projecting supporting beams, a primary baffle carriage movably mounted on said supporting beams, means to rectilinearly move said primary carriage, a secondary baffle carriage movably carried within said primary carriage, a vertically disposed shaft rotatably mounted on said secondary carriage, a baffle mounted on said shaft for axial movement with respect thereto, means for effecting axial movement of said baffle along said shaft, means to reciprocate said secondary carriage and said baffle, and means to change the stroke of reciprocation of said secondary carriage and said baffle, said baffle being provided on both faces with a plurality of angularly disposed ribs, said ribs each being positioned at a 40° angle from the horizon-

tal and pointing downwardly toward the outer end of said baffle.

7. In a pulpwood box car unloader of the character described, a plurality of laterally projecting supporting beams, a primary baffle carriage movably mounted on said supporting beams, means to rectilinearly move said primary carriage, a secondary baffle carriage movably carried within said primary carriage, a vertically disposed shaft rotatably mounted in said secondary carriage, a baffle mounted on said shaft for axial movement with respect thereto, means for effecting axial movement of said baffle along said shaft, means to reciprocate said secondary carriage and said baffle, means to change the stroke of reciprocation of said secondary carriage and said baffle, said baffle being provided on both faces with a plurality of angularly disposed ribs, said ribs each being positioned at a 40° angle from the horizontal edge and pointing downwardly toward the outer end of said baffle.

8. In a pulpwood box car unloader of the type wherein is provided a primary cradle tilttable about a transverse axis, a secondary cradle pivotally attached to said primary cradle and tilttable about a longitudinal axis with respect thereto, car-carrying rails secured to the upper face of said secondary cradle, means for clamping a box car on said rails, means to tilt said primary cradle and means to tilt said secondary cradle; the combination of a primary carriage mounted on said secondary cradle adjacent said box car to be unloaded, means to move said primary carriage into or away from said box car, a secondary carriage movably carried within said primary carriage, a ribbed baffle extending from said secondary carriage, and means to reciprocate said baffle and secondary carriage.

9. In a pulpwood box car unloader of the type wherein is provided a primary cradle tilttable about a transverse axis, a secondary cradle pivotally attached to said primary cradle and tilttable about a longitudinal axis with respect thereto, car carrying rails secured to the upper face of said secondary cradle, means for clamping a box car on said rails, means to tilt said primary cradle and means to tilt said secondary cradle; the combination of a primary carriage mounted on said secondary cradle adjacent said box car to be unloaded, means to move said primary carriage into or away from said box car, a secondary carriage movably carried within said primary carriage, a ribbed baffle extending from said secondary carriage, means to reciprocate said baffle and secondary carriage, means to vary the speed of reciprocation of said baffle and secondary carriage, and means to vary the stroke of said baffle and secondary carriage.

10. In a pulpwood box car unloader of the type wherein is provided a primary cradle tilttable about a transverse axis, a secondary cradle pivotally attached to said primary cradle and tilttable about a longitudinal axis with respect thereto, car carrying rails secured to the upper face of said secondary cradle, means for clamping a box car on said rails, means to tilt said primary cradle and means to tilt said secondary cradle; the combination of a primary carriage mounted on said secondary cradle adjacent said box car to be unloaded, means to move said primary carriage into or away from said box car, a secondary carriage movably carried within said primary carriage, a ribbed baffle extending from said sec-

ondary carriage, means to reciprocate said baffle and secondary carriage, and means to vertically adjust the height of said baffle relative to said carriages.

11. Wood ejecting means for a pulpwood box car unloader having a loaded box car secured thereon and comprising a primary carriage located adjacent the box car and movable laterally with respect thereto, a secondary carriage reciprocably mounted on said primary carriage, 10 a ribbed baffle extending from said secondary carriage, means to move said primary and secondary carriages and said baffle bodily toward or away from the box car, and means to reciprocate

said secondary carriage and baffle with respect to said primary carriage.

CANEY A. THOMPSON.
